SILENCER FOR OUTSIDE INSTALLATION

John P. Tyskewicz, Hartford, Conn., assignor to
 The Maxim Silencer Company, Hartford,
 Conn., a corporation of Connecticut

Application April 18, 1951, Serial No. 221,634

2 Claims. (Cl. 181—55)

1

The present invention relates to silencers for diesel or gas engine exhausts where it is desirable to have the silencer mounted outside a building. In such cases the exhaust pipe of the engine usually comes through the wall horizontally at a distance from the ground, and the tail pipe from the silencer usually extends vertically to the top of the building to carry off the gases. For economical reasons it is desirable to have the silencer supported as close to the ground as possible. The combination of these requirements means that the inlet to the silencer should be horizontal and near the top of the silencer shell, while the outlet from the silencer should leave the shell in a vertical direction. It is the object of the invention to provide a silencer subject to the conditions above which will have good silencing properties and which will produce only slight back pressure.

The invention will now be described with reference to the accompanying drawings, in which:

Fig. 1 is a side elevation of a silencer with the cylindrical shell and certain other parts broken away on the median plane;

Fig. 2 is a section on line 2—2 of Fig. 1; and

Figs. 3, 4 and 5 are details showing different possible ways of mounting the inlet conduit.

The silencer comprises a cylindrical shell or casing 10, preferably of circular cross section, having a top header 11 and a bottom header 12 which may rest on any suitable foundation. Within the casing is a transverse partition 13 which divides the interior of the shell into a top or inlet chamber 14 and a bottom or outlet chamber 15. A conduit 16, open at both ends, passes through an aperture in the partition 13 and is supported from the latter as by welding. An outlet conduit 17 extends through the header 11 and is supported by it, and then passes coaxially through the conduit 16 and beyond it to a point near the bottom header 12, where it terminates with an open end. The conduit 16 is preferably coaxial with the shell 10, but may if desired be displaced sideways in a direction away from the inlet conduit to be described later. The space between the conduits 16 and 17 forms an annular passage 18 through which the exhaust gas may pass from the inlet chamber 14 to the outlet chamber 15, the conduits being held in the desired relation as by lugs 19.

The side inlet conduit 20 is in the preferred form located well up toward the top of the silencer casing, as shown in Fig. 1, although the silencer functions practically as well with the side inlet near the lower end of the inlet chamber 14 as shown at 202 in Fig. 4. When the inlet con-

2

nexion is near the top, a curved baffle plate 21 is secured adjacent the upper side of the inlet opening and curves downwardly over it. The entering gas is thus directed downwardly away from the open end of the annular passage 18 and has a chance to expand and to even out pressure pulses before passing down through the annular passage 18 into chamber 15. The plate 21 changes the direction of the gas very smoothly until it is nearly parallel to the axis of the silencer, resulting in a better silencing action and a lower back pressure than if the gas were directed circumferentially to produce whirling as is shown for contrast at 201 in Fig. 3. The downwardly directed inlet conduit of Fig. 5 is substantially the same in its action as the plate 21. In chamber 15 further evening out of the pulses occurs, and the gas finally passes up the central conduit 17 and out through the outlet connection 22.

Conduit 16 has a row of anti-resonance holes 23 located on the side away from the inlet connection 20, and conduit 17 has a row of similar holes 24 located on the side opposite holes 23. This arrangement results in a particularly excellent anti-resonating system, which is assisted by the provision of a slot 25 at the lower end of conduit 17. No great amount of gas passes through holes 23 and 24, although they may aid in the smoothing out of high pressure peaks, their main purpose being to suppress the tendency of the gas columns within the annular passage 18 and the conduit 17 to resonate at frequencies dependent upon the lengths of these passages. The size and location of the holes should be determined as described in Bourne Patent 2,297,046, September 29, 1942. The conduit 17 has a length within the silencer great enough to act as a self-contained tail pipe, although generally an additional tail pipe is used for the purpose of carrying the gases upwardly the necessary distance. In figuring the length of the conduit 17 so that the holes 24 may be located at the half and quarter points as described in the Bourne patent referred to, two thirds of the portion of the conduit containing the slot 25 is omitted since one effect of the slot is to shorten the acoustic length of the conduit 17 by approximately the amount indicated above. In the case of the open-ended cylinder 16 the location of the holes at the half and quarter points is uncomplicated.

What I claim is:

1. A silencer comprising a substantially cylindrical shell having end headers and being divided into an inlet and an outlet chamber by a transverse partition; said silencer having an open-

ended cylinder passing through the partition and terminating at each end at a point between the partition and the respective end header, an inlet conduit opening into the inlet chamber adjacent that end of the open-ended cylinder in the inlet chamber, a curved plate secured to the shell adjacent the upper portion of the inlet conduit and curved downwardly over the opening of said conduit, and an outlet conduit passing through an end header, through a portion of the inlet chamber, through the interior of the open-ended cylinder, through a portion of the outlet chamber, and terminating within the latter at a point between the end of the open-ended cylinder and the adjacent end header, said open-ended cylinder being imperforate on the side adjacent the inlet conduit and having on the opposite side a single row of perforations located at half and quarter points along its length, and the outlet conduit being imperforate on said opposite side where it passes through the open-ended cylinder and having on the side adjacent the inlet conduit a single row of holes located at half and quarter points along its effective acoustic length.

2. A silencer comprising a substantially cylindrical shell having end headers and being divided into an inlet chamber and an outlet chamber by a transverse partition, said silencer having an open-ended cylinder passing through the partition and terminating at each end at a point between the partition and the respective end header, an inlet conduit opening into the inlet chamber adjacent that end of the open-ended cylinder in the inlet chamber, a curved plate secured to the shell adjacent the upper portion of the inlet conduit and curved downwardly over the

opening of said conduit, and an outlet conduit passing through an end header, through a portion of the inlet chamber, through the interior of the open-ended cylinder, through a portion of the outlet chamber, and terminating within the latter at a point between the end of the open-ended cylinder and the adjacent end header, said outlet conduit having a longitudinally extending slot in the portion thereof extending into the outlet chamber beyond the open-ended cylinder and being imperforate on the side opposite the inlet conduit and having a single row of perforations located at half and quarter points along its effective acoustic length within the open-ended cylinder on the side adjacent the inlet conduit, and the said open-ended cylinder being imperforate on the side adjacent the inlet conduit and having a single row of perforations located at half and quarter points along its length on the side opposite the inlet conduit.

JOHN P. TYSKEWICZ.
